APPAREL SUPPORTER

Robert J. Hodge, West Haven, Conn., assignor to
The American Buckle Company, West Haven,
Conn., a corporation of Connecticut

Application November 25, 1940, Serial No. 366,938

8 Claims.

(Cl. 24—73)

This invention relates to improvements in supporters for apparel, and is particularly adapted for use on overalls-suspenders, and may be used on any apparel where it is desired to have a supporting device engageable with and disengageable from an engaging-member, such as a button or the like.

One object of this invention is to provide an improved retaining or supporting device which may be readily engaged with or disengaged from an engaging-member such, for example, as a button or the like, but which will be less likely to become accidentally disengaged from the engaging-member.

Another object of this invention is to provide an improved retaining or supporting device which can be readily manufactured at low cost and which is of substantially-rigid, durable construction not readily damaged by laundering operations.

With the above and other objects in view, as will appear to those skilled in the art from the present disclosure, this invention includes all features in the said disclosure which are novel over the prior art.

In the accompanying drawings forming part of the present disclosure, in which certain ways of carrying out the invention are shown for illustrative purposes:

Fig. 1 is a front view illustrating one embodiment of the invention;

Fig. 2 is a side view of Fig. 1;

Fig. 3 is a cross-sectional enlarged view on line 3—3 of Fig. 1;

Fig. 4 is a front view on an enlarged scale similar to Fig. 1 but illustrating the retaining- and engaging-members in partly-disengaged position;

Fig. 5 is a cross-sectional view on line 5—5 of Fig. 4;

Fig. 6 is a front view similar to Fig. 4 but with the engaging-member or button being engaged with or disengaged from the retaining-member by a somewhat different mode of procedure;

Fig. 7 is a perspective view of the retaining-member per se;

Fig. 8 is a front view of a modified form of retaining-member;

Fig. 9 is another modified form of retaining-member in the form of a buckle made of sheet-metal;

Fig. 10 is a rear view of Fig. 9;

Fig. 11 is a vertical cross-sectional view on line 11—11 of Fig. 9;

Fig. 12 is a horizontal sectional view on line 12—12 of Fig. 9;

Fig. 13 is a front view similar to Fig. 9 of another modified form of retaining-member;

Fig. 14 is a perspective view similar to Fig. 7

of another modification of the form of retaining-member shown in Fig. 7; and

Fig. 15 is a perspective view similar to Fig. 14 of still another modified form of retaining-member.

In the description and claims, the various parts and steps are identified by specific names for convenience, but they are intended to be as generic in their application as the prior art will permit.

10 In carrying out the invention in the way illustrated in Figs. 1 to 7 of the drawings, an apparel-supporter or retaining-device 20 is illustrated as applied to a strap 21 of overalls-suspenders, for detachable connection with an engaging-member

15 22 in the form of a button secured to the bib 23 of the overalls. The retaining-device 20 includes a frame-portion 24 which includes the upper frame-bar 25 supported in the loop of the strap 21, and lower frame-bar portions 26, 27 which

20 are integral with the depending retaining-member or retaining-loop 28 provided with a retaining-opening 29 which is provided with a mouth 30 formed with guide-lips 31, 32 which are reversely inclined or oppositely inclined to the general plane of the retaining-member 28.

25 The engaging-member or button 22 is secured on the overalls-bib by any suitable means such, for example, as by a usual form of fastening means in the form of a rivet-like member 33. The button 22 includes a head 34 and a shank 35.

30 The particular form of retaining-device 20 shown in Figs. 1 to 7 is formed of a wire having its two ends welded together at 36, and with the lower major portion of the wire of the frame-member flattened as illustrated. The retaining-device 20 is preferably made of sufficiently stiff wire to result in a supporting device which is strong and substantially rigid and effectively resists distortion or damage from laundering operations.

35 As illustrated in Fig. 1, the shank 35 of the button 22 normally is supported at the lower end of the retaining-opening 29. The size of the retaining-opening 29, the distance between the lips 31 and 32 and the amount of opposite deflection

40 or inclination of the lips from the general plane of the retaining-member are such, that in order to detach the retaining-member 20 from the engaging-member 22, or, in order to permit of a simpler word description, to detach the engaging-member or button 22 from the retaining-member 20, the button 22 is first moved upward and to the right relatively to about the widest portion of the opening 29 with the shank 35

45 against the right edge of the opening, whereupon the button 22 is tilted about an upstanding or vertical axis (Figs. 4 and 5) which permits the left edge-portion of the head 34 of the button 22 to swing past the left side of the opening 29, whereupon the button is moved to the left to

carry the button-head out of the opening 29 to thus detach it from the retaining-member by removing it entirely away from the opening 29. In order to again engage the parts together, the reverse of the procedure which has just been described is gone through to again bring the head 34 into position through the opening 29 and finally with the shank 35 resting in the position shown in Fig. 1.

Instead of disengaging or engaging the parts in the manner which has just been described, the mode of procedure can be formed somewhat differently. Thus, after the head 34 has been tilted to the position shown in Figs. 4 and 5, instead of moving the head toward the left of Fig. 1, it can be moved almost vertically upward to bring an edge-portion of the head 34 between the oppositely-inclined lips 31 and 32, as illustrated in Fig. 6, after which, movement of the head to the left will entirely detach it from the opening 29. And, similarly, the members can be engaged by the reverse of the operation just described for disengaging the member.

Attention is called to the fact that the mouth 30 formed by the lips 31 and 32 is narrower than the diameter of the shank 35 so that the latter cannot pass upward through the mouth 30. This is important in order to prevent the accidental disengagement of the parts while they are being worn. Attention is also called to the fact that the vertical or upstanding length of the retaining-opening 29 is preferably less than 1½ times the corresponding length of the head 34, and still more preferably, is only slightly longer than the length of the head, in order to further minimize the danger of accidental disengagement of the parts.

The oppositely-deflected or -inclined guide-lips 31 and 32 facilitate the ready insertion of the button-head and the ready removal thereof when it is definitely desired or intended to bring about this procedure, the edge portions of the oppositely-deflected guide-lips 31 and 32 definitely serving to guide the opposite faces of the edge portion of the button-head 34 in its operation of being engaged with or disengaged from the retaining-device 20.

In the form of the invention illustrated in Fig. 8, the construction is similar to that shown in Figs. 1 to 7 inclusive, with the principal exception that the form of the retaining-opening 29a of the retaining-device 20a is of different shape due mainly to there being a disengagement-inhibiting projection 37 which aids in inhibiting the accidental disengagement of the button-head from the retaining-member or -loop 28a. The shank of a button engaged with the loop 28a normally rests at the lower end of the loop, and when the button is being disengaged from the loop the shank of the button is moved upward to the right to bring it against the right side of the loop before tilting it about an upstanding axis preparatory to moving the button out of the retaining-opening 29a of the loop.

In the form of the invention illustrated in Figs. 9 to 12 inclusive, the retaining-device 38 is formed of sheet metal in the form of what is known as a buckle having the plurality of strap-openings 39. The depending retaining-member 40 has a retaining-hole or -opening 41 with a disengagement-inhibiting projection 42 and with guide-lips 43 and 44 which are oppositely inclined or deflected to the general plane of the retaining-member. The mode of engaging an engaging-member or button with, and disengag-

ing it from, the retaining-opening 41 is similar to that described in connection with Figs. 3, 4 and 5.

In the form of the invention illustrated in Fig. 13, the retaining-device 38a and its mode of use is similar to the one illustrated in Figs. 9 to 12, differing therefrom mainly in the opening 41a which has no oppositely-deflected lips, the entire edge portion of the depending retaining-member 40a adjacent the edge of the opening 41a being in the plane of the main central part of the depending sheet metal retaining-member 40a.

The modified form of retaining-device illustrated in Fig. 14 is substantially the same as that illustrated in Figs. 1 to 7 inclusive with the exception that the lip 45 is not deflected, while the lip 46 is downwardly deflected. The modified form of retaining-device shown in Fig. 15 is very similar to that shown in Fig. 14 except that the lip 47 is deflected upwardly while the lip 48 is not deflected at all. The mode of engaging either of these retaining-members shown in Figs. 14 and 15 with an engaging-member or disengaging it from an engaging-member is essentially the same as has been set forth concerning the construction shown and described concerning Figs. 1 to 7 inclusive.

In the case of all of the forms of the invention illustrated in the drawings, the retaining-opening preferably has a vertical length of less than 1½ times the vertical length of the head of the engaging-member and preferably is only slightly more than the vertical length of the head of the engaging-member in order that the head shall have just sufficient room to be readily disengaged from or engaged with the retaining-member subsequent to the tilting action about an upstanding axis which has been previously described. It will also be observed that it is impossible for the shank of the button or engaging-member to become disengaged accidentally from the engaging-member by the shank passing upwardly through the mouth or throat of the retaining-member in those forms of the invention where there is a mouth or throat, and, of course, where there is no mouth or throat, as in the case of the forms of the invention illustrated in Figs. 9 to 13 inclusive, the shank cannot become disengaged by passing upwardly through any mouth.

In engaging or disengaging the parts, it is usually more convenient to manipulate the retaining-device instead of the button, but it requires simpler and less cumbersome language to describe the operation as though the button were the part being manipulated, and therefore in this application, the latter mode of description will ordinarily be used. In the claims the term "relatively" is used to clearly indicate that it is immaterial as to which part is actually moved.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A new article of manufacture of the class described for use with an engaging-member having a head and a shank, comprising: a retaining-device including a depending retaining-member provided with a retaining-opening and engage-

able with and disengageable from an engaging-member having a head and a shank; said retaining-member being constructed and arranged to be disengageable from said engaging-member by tilting said head about an upstanding axis relatively to said retaining-member, and moving said tilted head relatively under a portion of said retaining-member adjacent said opening, and out of said opening; said engaging-member not being disengageable from said retaining-member by an upward movement without the said tilting of said head about said upstanding axis.

2. A new article of manufacture of the class described for use with an engaging-member having a head and a shank, comprising: a retaining-device including a depending retaining-member provided with a retaining-opening and engageable with and disengageable from an engaging-member having a head and a shank; said retaining-member being constructed and arranged to be disengageable from said engaging-member by tilting said head about an upstanding axis relatively to said retaining-member, and moving said tilted head relatively under a portion of said retaining-member adjacent said opening, and out of said opening; said engaging-member not being disengageable from said retaining-member by an upward movement without the said tilting of said head about said upstanding axis; and there being a disengagement-inhibiting projection at one side of said opening.

3. A new article of manufacture of the class described for use with an engaging-member having a head and a shank, comprising: a retaining-device including a depending retaining-member provided with a retaining-opening and engageable with and disengageable from an engaging-member having a head and a shank; said retaining-member being constructed and arranged to be disengageable from said engaging-member by tilting said head about an upstanding axis relatively to said retaining-member, and moving said tilted head relatively under a portion of said retaining-member adjacent said opening, and out of said opening; said engaging-member not being disengageable from said retaining-member by an upward movement without the said tilting of said head about said upstanding axis; and there being a guide-lip at the upper end of said opening inclined to the general plane of said retaining-member.

4. A new article of manufacture of the class described, for use with an engaging-member having a head and a shank, comprising: a retaining-device including a depending retaining-member provided with a retaining-opening and engageable with and disengageable from an engaging-member having a head and a shank; said retaining-member being constructed and arranged to be disengageable from said engaging-member by tilting said head about an upstanding axis relatively to said retaining-member, and moving said tilted head relatively under a portion of said retaining-member adjacent said opening, and out of said opening; said engaging-member not being disengageable from said retaining-member by an upward movement without the said tilting of said head about said upstanding axis; and there being a pair of spaced-apart guide-lips at the upper end of said opening oppositely inclined to the general plane of said retaining-member.

5. A new article of manufacture of the class described for use with an engaging-member having a head and a shank, comprising: a retaining-device including a depending retaining-member provided with a retaining-opening and engageable with and disengageable from an engaging-member having a head and a shank; said retaining-member being constructed and arranged to be disengageable from said engaging-member by

10 tilting said head about an upstanding axis relatively to said retaining-member, and moving said tilted head relatively under a portion of said retaining-member adjacent said opening, and out of said opening; said engaging-member not being disengageable from said retaining-member by an upward movement without the said tilting of said head about said upstanding axis; and the vertical length of said opening being less than one-and-one-half times the vertical length of said head.

15 6. A new article of manufacture of the class described for use with an engaging-member having a head and a shank, comprising: a retaining-device including a depending retaining-loop providing a retaining-opening having a mouth; said retaining-loop being engageable with and disengageable from an engaging-member having a head and a shank, and being constructed and arranged to be disengageable from said engaging-member by tilting said head about an upstanding axis relatively to said retaining-loop, and moving said tilted head relatively under a portion of said retaining-loop adjacent said opening, and out of said opening; said shank not being passable through said mouth.

20 7. A new article of manufacture of the class described for use with an engaging-member having a head and a shank, comprising: a retaining-device including a depending retaining-loop providing a retaining-opening having a mouth formed with lips; said retaining-loop being engageable with and disengageable from an engaging-member having a head and a shank, and being constructed and arranged to be disengageable from said engaging-member by tilting said head about an upstanding axis relatively to said retaining-loop, and moving said tilted head relatively under a portion of said retaining-loop adjacent said opening, and out of said opening; said shank not being passable between said lips; and one of said lips being inclined to the general plane of said retaining-loop to form a guide-lip.

25 8. A new article of manufacture of the class described for use with an engaging-member having a head and a shank, comprising: a retaining-device including a depending retaining-loop providing a retaining-opening having a mouth formed with lips; said retaining-loop being engageable with and disengageable from an engaging-member having a head and a shank, and being constructed and arranged to be disengageable from said engaging-member by tilting said head about an upstanding axis relatively to said retaining-loop, and moving said tilted head relatively under a portion of said retaining-loop adjacent said opening, and out of said opening; said shank not being passable between said lips; and said lips being oppositely inclined to the general plane of said retaining-loop to form a pair of guide-lips.

ROBERT J. HODGE.
